UNITED STATES PATENT OFFICE.

AMOS L. KNIGHT, OF PHILADELPHIA, PENNSYLVANIA, ASSIGNOR TO LANSTON MONO-TYPE MACHINE COMPANY, OF PHILADELPHIA, PENNSYLVANIA, A CORPORATION OF VIRGINIA.

MANUFACTURE OF PRINTERS' LEADS, RULES, &c.

1,256,806.

Specification of Letters Patent. Patented Feb. 19, 1918.

Application filed July 27, 1916. Serial No. 111,741.

To all whom it may concern:

Be it known that AMOS L. KNIGHT, a citizen of the United States, residing at Philadelphia, in the county of Philadelphia and State of Pennsylvania, have invented certain new and useful Improvements in the Manufacture of Printers' Leads, Rules, &c.; and I do hereby declare the following to be a full, clear, and exact description of the same, reference being had to the accompanying drawings, forming part of this specification.

The present invention relates to improvements in the manufacture of leads, rules, etc., which constitute elements of printing forms, and more particularly to the manufacture of such elements when formed or cast in successive increments, fused together at their proximate or meeting edges. Machines for casting printers' rules, leads, etc., of type metal in successive increments joined together at their proximate edges by fusion, such as set forth in a prior application filed by me on October 3, 1914, Serial No. 864,894, now Patent No. 1,222,415, dated April 10, 1917, have become well known in the art, and this type of machine, therefore, needs no detail description for an understanding of the present invention.

In the formation or casting of these strip elements of printing forms in successive increments, considerable difficulty has been experienced in the production of strips of accurately uniform height, that is to say, in that dimension of the strip which corresponds to the height of the type. This difficulty I have discovered is due to an unequal shrinkage in the metal, as it freezes and cools, with the result that the height of each increment will vary between the edge which joins the preceding increment and the edge which joins the succeeding increment.

The object of the present invention is to overcome this difficulty, and in accomplishing this end I have found that if each increment is initially made of varying height, in accordance with the variation in the degree of shrinkage, as the metal freezes and cools the final result will be a strip of uniform height, the edge of which will constitute a true and perfect printing surface.

In the accompanying drawings,— Figure 1 is a more or less diagrammatic representation of a short section of a print-

er's rule, showing the defect in the upper edge due to non-uniform contraction of the metal in freezing and cooling.

Fig. 2 is a similar view of a short section of a printer's rule of uniform height throughout.

Fig. 3 is a view corresponding to Fig. 2 and showing in dotted lines the initial form of one of the increments.

Fig. 4 is a diagrammatic sectional elevation, showing a mold in dotted lines with a mold blade and a matrix for giving the proper initial formation to the increments of type metal as they are cast.

In all of the views it will be understood that the variation in height is exaggerated in order to illustrate the invention more clearly.

In said drawings, Fig. 1 shows a section of a printer's rule or lead, which has been cast in successive increments 5, 5, etc., the dotted lines indicating the proximate edges of successive increments. Each succeeding increment has been added to the left hand edge of preceding increments, under which conditions it will be noted that the forward edge of each increment or that edge toward the right is of greater height than the rear or left hand edge, this being due to the fact that at the edge where the succeeding increments fuse with the edge of the preceding increments, the shrinkage of the metal is less than at the opposite edge.

In Fig. 2 a strip or rule of proper formation is illustrated, wherein it will be noted that each increment 6, 6, 6, etc., is of uniform height, and as a result, the entire strip is of uniform height, or in other words, the top edge of each increment alines with the top edges of preceding increments.

In Fig. 3, the strip shown in Fig. 2 is illustrated and in addition there is shown in dotted lines at 7 an increment which is given its proper initial formation; that is to say, its upper edge 8 is inclined upwardly from the point where it meets the preceding increment, thus producing an initial formation which is lower at its forward edge than at its rear edge, under which circumstances, the shrinkage of the metal is such that when frozen and cooled each increment is of a uniform height with upper edges in alignment.

In Fig. 4 there is indicated in dotted lines

at 9, a mold having a mold cavity in which the increments are formed successively, molten metal being injected into said cavity through a nozzle 10 and the upper portion 5 of the cavity being formed by a matrix 11. A mold blade 12 is adapted to reciprocate in the cavity and to normally form its rear wall, while the preceding increment of frozen metal forms the front wall of said 10 cavity. Said metal is retained in position by the forwardly projecting portions of the mold, until it is advanced by the reciprocation of the mold blade to form a space or cavity for the reception of the next increment. The matrix 11 is formed with a matrix cavity or recess which gradually varies in depth or drive as indicated by the inclined 15 top wall 13, the inclination being shown as slightly exaggerated in the drawings, and the greatest depth being at the rear or left hand edge of the cavity. Its least depth is 20 approximately at the point where the preceding increment of the rule remains to form the forward edge wall of the cavity. The matrix drive or recess preferably extends 25 beyond the last mentioned point and is preferably provided with a slightly flared or inclined discharge or exit extension to give clearance to the frozen metal as it is pushed 30 out of the cavity.

In the formation of matrices of this kind, difficulty has been experienced in making the depth of the drive or matrix cavity accurately so as to correspond to the shrinkage 35 of the metal in freezing and cooling and in the preferred method of manufacture the matrix cavity is first made of uniform depth throughout and the matrix is subsequently bent slightly at a point which substantially 40 corresponds to the forward or right hand edge of the mold cavity. To facilitate this bending, a transverse cut or kerf 14 is formed in the matrix. After the bending of the matrix in the manner indicated the top 45 and bottom faces are dressed off parallel with each other and to an extent which will provide for the proper depth of the matrix cavity.

This procedure in the manufacture of 50 matrices greatly simplifies their production and permits of the formation of matrix cavities of complex or ornamental designs which will vary in depth to exactly the proper degree to produce borders for ornamental rules 55 having true printing surfaces which will exactly correspond to the height of the printing surfaces of the other portions of the printing form; in other words, they will be uniformly type-high throughout.

60 What is claimed is:

1. The improvement in the art of casting printers' leads, rules, etc., in successive in-

crements fused together at their proximate edges, which consists in initially forming each increment of greater height at one of 65 said edges than at the other, whereby the contraction of the metal in freezing and cooling will bring the top edges of the increments into alinement with each other and produce a strip of uniform height. 70

2. The improvement in the art of casting printers' leads, rules, etc., in successive increments fused together at their proximate edges, which consists in initially forming each increment of greater height at its rear 75 edge, than at its forward edge, where it joins the preceding increment, whereby the contraction of the metal in freezing and cooling will produce a strip of uniform height.

3. The improvement in the art of casting 80 printers' leads, rules, etc., in successive increments fused together at their proximate edges, which consists in initially forming each increment of greater height at one of 85 said edges than at the other, and in fusing the edge of less height to the edge of the preceding increment, whereby the contraction of the metal in freezing and cooling will produce a strip of uniform height.

4. In an apparatus for casting printers' 90 leads, rules, etc., in successive increments fused together at their proximate edges, the combination of the following instrumentalities, to wit, a mold having a cavity open at one side, a mold blade mounted to reciprocate in said cavity with means for holding a previously cast increment in position to close the open side and form one wall of the mold cavity and a matrix forming one wall of said mold cavity having a matrix cavity therein 100 graduated in depth in accordance with the shrinkage of the metal in freezing.

5. In apparatus for casting printers' leads, rules, etc., in successive increments, fused together at their proximate edges, a matrix 105 for forming one edge of said lead or rule, said matrix having a matrix cavity therein the top wall of which is of gradually diminishing depth toward the exit side.

6. A matrix for forming printers' leads, 110 rules, etc., of successive increments fused together at their proximate edges formed with a matrix cavity therein the top wall of which is of gradually diminishing depth toward the exit end of the cavity. 115

7. A matrix for casting printers' leads, rules, etc., in successive increments fused together at their proximate edges having a matrix cavity therein the top wall of which is of gradually diminishing depth toward 120 the exit end, and with a flaring discharge extension.

AMOS L. KNIGHT.
